UNITED STATES PATENT OFFICE.

CALE J. SCHNEIDER, OF TOLEDO, OHIO, ASSIGNOR TO THE DE VILBISS COMPANY, OF TOLEDO, OHIO, A CORPORATION OF OHIO.

NIGHT LAMP.

Application filed January 27, 1928. Serial No. 249,832.

This invention relates to lamps of the character intended primarily for use in bedrooms and sick rooms, and has for its object the provision of such a lamp which is ornamental and attractive in appearance, adapted to produce a mellow or subdued glow in the room, and is capable of use to vaporize liquids of a medicinal or scent giving character.

The invention is fully described in the following specification and one embodiment thereof illustrated in the accompanying drawings, in which,—

Figure 1 is a front elevation of a device embodying the invention with parts broken away. Fig. 2 is a central vertical section on the line 2—2 in Fig. 1 with parts in full. Fig. 3 is a cross-section on the line 3—3 in Fig. 1 with a part broken away, and Fig. 4 is a fragmentary perspective view of a lower corner portion of the device with the supporting leg removed.

Referring to the drawings, 1 designates a frame comprising, in the present instance, a bottom cross-piece 2 and the two uprights 3, 3 fixedly rising from the ends of said cross-piece. The uprights 3 are of U or channel form in cross-section with their channels opening toward each other to permit a plate 4 to be slidably mounted therein. The upper ends of the standards are rolled outwardly for ornamental effect. The frame 1 being open at its upper end, the plate 4 may be slidably lowered into or removed therefrom.

The plate 4 is preferably of colored or translucent glass to permit rays of light passing therethrough to be subdued or mellowed, and is also preferably decorated to give it an attractive and ornamental appearance.

A plate 5, preferably of sheet metal, is secured at its lower edge to the front side of the cross-piece 2, being, in the present instance, substantially coextensive with the width of the space between the two uprights 3 and extending a short distance above the cross-piece 2 in front of the plate 4 and carrying at its upper end a frame 6 for holding a medallion 7, or other ornamental member of translucent material, so that the directing of light rays therethrough will bring out in relief the ornamental figure appearing thereon. The frame 6 is provided at its front side with an inturned flange which retains the member 7 therein, and the back of the frame is closed by the plate 4. It is preferable to make the

upper portion of the plate 5 of ornamental form to lend to the attractiveness of the device.

The frame 1 is provided at each lower corner thereof with a bowed support or double leg member 8, and such corner portions are embraced by reinforcing corner pieces 9.

A bracket 10 is disposed at the rear side of the cross-piece 2 and has upturned ears 11 at its forward edge secured to the cross-piece by rivets 12. The bracket 10 is of ring form to permit the mounting of an electric socket base 13 therein, the socket of which extends upwardly to receive the electric light bulb 14, which latter is disposed at the rear of the lower portion of the plate 4 and medallion 7. The lower portion of the base 13 is enclosed by a casing 15, having a rearwardly extending opening therein through which the leads 16 for the base extend.

An opaque casing 17 of tubular form, in the present instance, encloses the lamp 14 and fits at its lower end down around the base 13. This casing has an opening 18 in its front side in advance of the lamp 14. The upper end of the casing 17 has a cup 19 removably suspended therein for receiving a perfume, medicine or other liquid to be vaporized. The upper end of the cup is closed by a removable cover 20 having openings therein through which the vapor arising from the liquid may escape. The pull-chain 21 for the socket base switch extends forwardly from the base 13 through a guide eyelet 22 projecting forwardly through the cross-piece 2.

It is apparent that I have provided a night lamp which is exceedingly attractive in appearance and which has the lamp so mounted and disposed with respect to the plate 4 that it is entirely hid from view by such plate, and the rays from the lamp are permitted to pass in a subdued manner through the plate and ornamental parts associated therewith. Should either the plate 4 or medallion member 7 be broken or for any other reason desired to be replaced, this can be easily and quickly done, as is apparent.

I wish it understood that my invention is not limited to any specific construction, arrangement or form of the parts, as it is capable of numerous modifications and changes without departing from the spirit of the claims.

Having thus described my invention, what

I claim as new and desire to secure by Letters Patent is:—

1. In a night lamp, a frame, members carried by the frame through which light rays may pass, a bracket projecting rearwardly from the frame and secured to its lower portion in supporting relation thereto, legs supporting the bracket, and light-creating means carried by the bracket and disposed at the rear of said members.
2. In a night lamp, a frame including a base and an upright portion, a translucent member carried by the upright portion of the frame, an electric lamp socket carried by the base at the rear side thereof, a lamp in said socket disposed at the rear of said member, an opaque casing member enclosing said lamp and spaced from said upright portion and having an opening at its front side between said lamp and member.
3. In a night lamp, a frame, a translucent member carried by the frame, an electric lamp socket carried by the frame at the rear side thereof, a lamp in said socket disposed at the rear of said member, an opaque casing member enclosing said lamp and having an opening at its front side between said lamp and member, a liquid receptacle mounted in the top of the casing and a cover over said receptacle and having openings therein.
4. In a night lamp, a frame, a translucent member carried by the frame, a smaller frame carried by the first frame in advance of said translucent member, a second translucent member carried by the smaller frame, and means at the rear of said translucent members

for causing a light to be directed therethrough.

5. In a night lamp, a frame having a cross-piece at its lower end and uprights rising from the opposite ends of said cross-piece, a translucent plate removably carried by said frame between said uprights, a rigid member rising from the cross-piece in advance of the plate and having a medallion-carrying frame, a translucent medallion carried by said second frame in advance of a portion of said plate, and means carried by the first frame and disposed at the rear of said plate and medallion to direct light therethrough.

6. In a night lamp, a frame of U-form with its leg portions channeled to form guideways, legs supporting said frame, a translucent plate removably carried by the frame with its side edges slidingly mounted in said guideways, a bracket carried by the base of the frame and projecting rearwardly therefrom, and an electrical light emitting means carried by said bracket at the rear of said plate.

7. In a portable night lamp, a base, an opaque casing supported by the base, a lamp mounted within said casing, said casing having an opening in its front side only through which the light may shine, and a translucent member supported by the base in front of said casing and spaced therefrom, said translucent member extending far enough laterally so that no direct rays from the lamp may pass the same.

In testimony whereof I have hereunto signed my name to this specification.

CALE J. SCHNEIDER.
